FRANK C. LAURIE, OF HOUSTON, TEXAS.

CAPPING DEVICE.

1,245,934.

Specification of Letters Patent.

Patented Nov. 6, 1917.

Application filed August 14, 1917. Serial No. 186,168.

To all whom it may concern:

Be it known that I, FRANK C. LAURIE, a British subject, residing at Houston, in the county of Harris and State of Texas, have 5 invented certain new and useful Improvements in Capping Devices, of which the following is a specification.

This invention relates to capping devices, and it relates more particularly to oil well 10 cappers.

It is well known that when oil wells have been drilled, the oil frequently flows therefrom in a very large volume and with great force, so that it is extremely difficult to attach 15 the desired pipe connections so as to control the flow of oil from these wells. Therefore:—

One of the objects of this invention is to provide a capping device that may be applied 20 with comparative ease and facility to an oil well or gusher of the greatest volume and force.

Another object of the invention is to provide a device of this character which is thoroughly 25 efficient, exceedingly strong and durable, and which may be manufactured at a comparatively small cost.

Other objects and advantages may become apparent to persons who read the following 30 description in connection with the accompanying drawings in which Figure 1 is a front elevational view of my improved oil well capper in its operative position.

Fig. 2 is a side elevational view of the construction 35 illustrated in Fig. 1, and of certain additional elements.

Fig. 3 is a horizontal sectional view, the section being taken on line 3—3 of Fig. 1.

Fig. 4 is a horizontal sectional view, the 40 section being taken on line 4—4 of Fig. 1.

Referring to these drawings in detail, in which similar reference characters correspond to similar parts throughout the several views, the numeral 10 indicates the upper 45 end portion of the well casing which extends approximately level with the earth's surface on which is supported a platform or foundation of boards or timbers 11 having an aperture 12. An upwardly tapering nozzle or connection 13 is secured to the casing 10 by means of a collar or coupling 14, the member 13 being provided with an enlargement or shoulder 15. A sleeve or packing element 16 is fitted around the upper end of 50 the element 13, and this sleeve is preferably formed of lead, although I may employ such

other material as may be found suitable and convenient.

A bell-shaped cap 17 is provided with a flange 18 which connects with a corresponding flange 19 on a T coupling 20, bolts 21 being employed for securing the flanges 18 and 19 together. Guiding arms 22 extend laterally from the flanges 18 and 19 and are provided with apertures through which a pair of draw rods 23 extend. Each of these rods 23 is bifurcated at its lower end and screw-threaded at its upper end. The bifurcated end of each rod 23 is provided with apertures in which a bolt or pivot 24 extends, and each of these members 24 also extends to the eye of an eye-bolt 25.

In order to place the nozzle 13 over the opening of the casing 10, I employ the clamp 26 illustrated in Fig. 4, a somewhat similar clamp 27 and a pair of screw-threaded rods 28. The clamp 26 comprises two counterpart plates or members which are formed with semi-cylindrical elements 29, 30, and 31, so that when these plates are fitted together, or oppositely disposed as in Fig. 4, the semi-cylindrical members combine to form hollow cylinders through which extend the elements 13, 25, and 28 respectively. The clamp 26 is provided with suitable recesses in which the shoulder 15 is seated. The clamp 26 is also provided with a plurality of apertures through which bolts 32 extend, these bolts being provided with nuts 33 which co-operate therewith for drawing the semi-cylindrical portions 29, 30, and 31 into clamping engagement with the elements 13, 25, and 28 respectively.

The clamp 27 is provided with semi-cylindrical portions 27^a and 27^b and with apertures through which bolts 35 extend, nuts 35^a co-operating with these bolts for drawing the clamping elements together upon the casing 10 and rods 28.

Nuts 28^a are provided upon the opposite ends of each rod 28, and by means of these nuts, the clamps 26 and 27 may be drawn toward one another, so that the nozzle 13 may be drawn tightly into engagement with the casing 10 and securely held in such engagement.

Pipe connections 36, 37, and 38, may be of such ordinary or preferred construction as to meet the particular requirements in each case, and may be secured together as usual.

In order to prepare the cap 17 and the connections 20, 36, 37, and 38, for connec-

tion with the nozzle 13, I provide a clamp 39, having semi-cylindrical elements 40 and 41, this clamp 39 being provided with bolts 39^a which coöperate with nuts 39^b, for drawing the clamping elements together upon the connection or pipe section 38. A clamp 43, of a construction somewhat similar to the clamp 39 and provided with similar bolts and nuts, embraces the pipe connection 36 and is provided with guide elements 44 through which the rods 23 extend.

Upon the T coupling 20 is mounted a valve 45, of any appropriate construction, and this valve may be directly connected with the T coupling 20, or it may be connected through the medium of a pipe section 46.

The pipe connection 37 preferably constitutes a valve, for a purpose which will be explained hereinafter.

The operation of this device is as follows:

Prior to capping the nozzle 13, the clamps 26, 27, and 39, as well as the guides 22 and 43, are secured in position on the respective elements with which they are normally engaged; but the pivots or bolts 24 are removed, and the elements 16 and 17 are disconnected from one another. Moreover, the nuts 23^a are disposed at the ends of the respective rods 23, while the bifurcated ends of these rods extend a considerable distance beyond the end of the bell-shaped connection 17. Now, it being desired to cap the nozzle 13, having the packing element 16 thereon; the pipe connections 17, 20, 36, 37, and 38, together with the clamps and guides 39, 43, and 22, and the rods 33, are moved bodily in a horizontal direction and in the longitudinal direction of the rods 23 until the bifurcated ends thereof have their apertures alined with the apertures of the eye-bolts 25. The bolts or pivots 24 are then placed in the alined apertures, so as to pivotally connect the rods 23 to the eye bolts 25. While in this position, the bell 17 is out of contact with the packing 16, and is out of range of the stream of oil which gushes from the nozzle 13; but when the bell or cap 17 and the rods 23, with their adjuncts, are swung upwardly into the vertical position, the bell 17 is disposed directly over the nozzle 13. Before thus raising the upper section of the capping device, the valve 37 is opened, while the valve 45 is closed, so that the oil continues to gush upwardly with comparatively little resistance. The nuts 23^a are now screwed downward, thereby co-operating with the clamps 26 and 39, and with their adjuncts for forcing the bell 17 down upon the packing 16, so as to make a fluid-tight connection with the nozzle 13.

At this stage of the operation, the oil continues to gush upward through the valve 37 and is prevented from flowing through the

valve 45, thereby allowing opportunity to connect this latter valve with the pipe line 47 without interference of the flowing oil. Now, the valve 45 may be opened, and the valve 37 closed, whereupon the flow of oil 70 is completely under control, and further waste thereof is entirely prevented.

From the foregoing, it will be seen that I have provided a device of this character which is thoroughly practical and efficient, 75 and which is extremely useful and valuable for the purpose specified.

Although I have described this form of my invention in minute detail, it is to be understood that my invention is not limited 80 to these exact details of construction and arrangements of parts, but I am entitled to make such alterations that do not constitute a departure from the inventive idea disclosed in this specification and claims.

What I claim as my invention is:

1. A well capping device comprising in connection with a well casing, a pipe connection adapted to be connected to the well casing, a pair of elements movably connected to the said pipe connection, a pair of elements secured to said well casing, means pivotally connecting the first said pair of elements with the second said pair of elements, and means for moving the first 90 said pair of elements with relation to the said connection, whereby the said pipe connection may be first swung into communicative relation with the well casing and thereafter moved downward into fluid-tight connection therewith.

2. A well capping device comprising in connection with a well casing, a nozzle on the well casing, a bell-shaped connection adapted to fit over said well casing, a pipe 105 connection, means through which the pipe connection communicates with said bell-shaped connection, a clamp secured on said pipe connection, a pair of draw rods, means coöperative with said clamp for moving said draw rods longitudinally with respect to the pipe connection and the bell-shaped connection, and means whereby said draw rods are pivotally connected to said well casing, so that the said bell-shaped connection may 115 be first moved into the position for receiving the liquid gushing from said nozzle and may be thereafter moved by the second said means into fluid-tight connection with said nozzle.

3. A well capping device comprising in connection with a well casing, a tapering nozzle fitting on the well casing, a bell-shaped connection, adapted to receive the tapered portion of said nozzle, a set of pipe 125 connections comprising a T-shaped connection and two valves, one branch of said T-shaped connection being secured to the said bell-shaped connection, one of said valves being connected to a laterally extending branch 130

of said T-shaped connection, and means for moving said set of pipe connections and bell-shaped connections bodily into fluid-tight connection with the said nozzle, whereby the liquid which flows from said casing may be allowed to pass through one of said valves while being prevented from passing through the other of said valves, so that the latter of said valves may be easily connected with a pipe line into which the liquid may be directed through the contiguous valve, by first opening said contiguous valve and thereafter closing the other of said valves.

4. The combination of a well casing, a capping device comprising a set of centrally alined pipe connections and a set of pipe connections extending laterally from the first said set of pipe connections, each said set

of pipe connections comprising a valve, a plurality of supporting members extending laterally from the first said set of pipe connections, a plurality of draw-rods engaged with said supports and each having an apertured end portion and a screw-threaded end portion, a plurality of apertured members pivotally connected respectively to the apertured ends of said draw-rod, and means whereby said apertured members are secured to said well casing, substantially as shown and for the purpose specified.

In testimony whereof I hereby affix my signature in presence of two witnesses.

FRANK C. LAURIE.
